SLIP

Samuel F. Bashara, Houston, Tex.

Application January 28, 1935, Serial No. 3,768

15 Claims. (Cl. 24—263)

The invention relates to an improvement in pipe engaging slips of the type generally used in connection with the handling of pipe in well drilling or pumping operations.

- 5 One of the objects of the invention is to provide a slip having renewable jaws or liners, each of the jaws having more than one toothed face so that a fresh face may be set to engage the pipe by merely adjusting the position of the slip parts.
- 10 Another object of the invention is to provide a slip having renewable jaws, each of which has a plurality of pipe engaging faces, and which may be turned to put any of the different parts in operative position.
- 15 Another object of the invention is to provide a renewable slip jaw having faces thereon adapted to fit different sizes of pipe.

Still another object of the invention is to provide a reversible dovetail jaw to give a double 20 useful life to the jaw itself.

Another object of the invention is to provide a removable slip jaw which is adapted to rock about a vertical axis to conform to the contour of the pipe supported, and, in addition, to provide for resilient means for holding the jaws 25 in a substantially aligned position when free from load.

A still further object of the invention is the provision of a renewable backing member for the 30 slip segments, and, when desired, for the provision of a resilient cushion between said backing member and the segment itself.

A further object of the invention is to provide a backing member for a slip segment which may be adapted to fit at least two different sized slip 35 bowls.

The invention contemplates broadly the provision of a slip in which the pipe jaws may be moved to give fresh pipe engaging areas without 40 placing the parts, and where the jaws are free to move slightly to align themselves with the pipe, and in addition, to adapt the jaws to be set to hold various sizes of pipe. It is also contemplated that a resiliently mounted backing member 45 may be provided on the back of the segments, this member being formed so that it may be set to adapt the slips to two different sized slip bowls.

Other advantages are thought to be apparent 50 when the following description is read in connection with the accompanying drawing, wherein:

Fig. 1 is a top plan view of a portion of a slip bowl in which are slips constructed in accordance with the invention, one of the segments

being cut away to show the details of construction.

Fig. 2 is a sectional view taken along the plane 2—2 of Fig. 1, and in the direction of the arrows.

Fig. 3 is a front view of a removable slip jaw 5 forming a part of the invention.

Fig. 4 is a top plan view of the jaw shown in Fig. 3.

Fig. 5 is a sectional view of the lower end of the slip segment seen in Fig. 2, showing a slightly 10 different form of construction.

Fig. 6 is a transverse sectional view taken along the plane 6—6 of Fig. 5, and in the direction indicated by the arrows.

Fig. 7 is a view similar to Fig. 6 showing the 15 operation of one feature of the invention.

Fig. 8 is a broken front elevation of a slip segment illustrating a somewhat different type of construction, but retaining the features of the invention.

Fig. 9 is a sectional view taken along the plane 9—9 of Fig. 8.

Fig. 10 is a sectional view taken through the jaw of Figs. 8 and 9 showing a suggested tooth profile.

The type of pipe engaging slip which I have designed is adapted to be seated within the usual downwardly tapered slip bowl 12. Each slip is made up of a plurality of segments 14 adapted to be positioned to engage the pipe or tubing 13. 30 Each segment is recessed on its forward face to receive a removable jaw or liner member 25. Said jaw is formed with a plurality of pipe engaging faces, each face of which is toothed to engage the pipe.

As seen in Fig. 3 each pipe engaging face of the jaw is formed with flattened areas 26 and 27, the areas 26 being cut more deeply in the toothed face of the jaw than are the areas 27.

Referring now to Fig. 2 the areas 26 and 27 engage the interior wall of the recess in the segment 14 which is shaped to receive the jaw and, because of their different depths, flattened areas interfit with the face of the segment leaving a space 23 allowing for relative longitudinal movement of the jaw on the segment. This permits a jarring action of the jaw on the segment when the device is released by the upward movement of the pipe 13.

The upper and lower ends of each jaw are recessed at 28 to interfit with a dowel 29 on the lower end and a cap screw 31 at the upper end thereof. The dowel and screw fit loosely in the recess so as to allow a slight play of the jaw on 50 55

its support for more ready adjustment of the jaw to the pipe.

As will be seen in Fig. 1, each jaw has its pipe engaging face recessed on an arc interfitting 5 with the rounded end or face 23 of the segment 14. This allows a rocking of the jaw on the segment to a certain limited extent which permits adjustment of the jaw to the pipe. There are four similar faces on the jaw shown in Fig. 1 10 and it will be obvious that where the cap screw 31 is removed the jaw may be partially rotated to present another face to the pipe where wear has taken place on the face originally employed. I am enabled, therefore, to provide four separate 15 pipe engaging faces to be employed before the jaw has become too dull for further use.

In Fig. 4 I have shown how the jaw may be varied from that shown in Fig. 1 to provide adjustment for the different sizes of pipe. In this 20 embodiment the jaws are slightly elongated in one direction, the faces, however, being similar in all respects to those shown in Fig. 1. The pipe engaging faces 34 will be adapted to engage a pipe of smaller diameter than are the two opposed 25 faces 35. The recesses 37 at the upper and lower ends of the jaw are elongated to interfit with the cap screw 31 and the dowel 29 when the jaw is mounted on the segment 14.

I have also provided a removable backing strip 30 39 by means of which the position of the segment 14 may be varied. The said backing strip 39 is preferably rectangular in cross-section and as shown in Figs. 6 and 7 they are fitted within recesses in the outer side of the segment 14'. As 35 the wear strip is wider in one direction than in the other it may be changed as to position within the recess to move the segment at different distances from the bowl in which the slip is seated.

In Fig. 6 the wear strip is placed with its 40 narrow thickness toward the bowl so as to fit a bowl of slightly larger diameter. In Fig. 7 the reverse is the case. These wear strips have at their upper end recesses to receive the cap screws 42 fitting within the recesses 41. I have shown 45 the lower end of each strip inserted within a tapered seat at the lower end of the recess which receives the strip as shown at 40. I may also provide a resilient pad of compressible material such as rubber 43 placed between the wearing 50 strip and the outer side of the segment 14.

Each segment is provided with one or more laterally extending arms 16 which are adapted to engage with similar arms on adjacent jaws to provide a hinged connection. The ends of these 55 arms are formed with an opening to receive a hinge bolt which allows a pivot connection between adjacent segments. Each arm is formed adjacent its end with lateral shoulders 17 which engage to limit the lateral swing of one segment 60 relative to the adjacent segment.

A plurality of jaws thus hinged together may form one complete slip. In Fig. 1 I have indicated three of such jaws hinged together and provided with a handle 19. Said handle is hinged at 65 its lower end to a pivot pin 21 mounted upon the upper end of a lug 21' on the central segment 14. It is also to be noted that each handle has an inwardly extending arm 22 which is adapted to engage the pipe when the handle 19 is swung upwardly. With reference particularly to Fig. 2 70 it will be seen that the upward swinging of the handle 19 will engage the arm 22 with the pipe tending to move the jaw outwardly away from the pipe compressing the pad 43 and allowing 75 the release of the jaws from engagement with

the pipe and starting the upward movement of the segment from the slip bowl.

In place of the rubber pad 43 I may place a spring shown at 45 in a recess 46 at the lower end of the segment, the spring being adapted to bear against the wear strip 47. I have also shown the lower end of the wear strip as being provided with a recess 48 to receive a dowel 49 upon which it is loosely mounted. The spring 46 tends to move the lower end of the wear strip against 10 the slip bowl and allow a slight movement thereof which permits release of the jaw from the pipe on the upward movement of the handle 19 as previously described.

While the jaws are preferably made in the 15 form shown in Fig. 1 and Fig. 5, I may mount them as shown in Figs. 8 and 9. In this case the segment 51 is shown as rounded on its outer side to engage the slip bowl and the wear strip 39 is omitted. The jaw member 51 has two pipe 20 engaging faces either of which may be presented outwardly to engage the pipe. The forward face of the segment 51 has a dove-tailed recess 52 into which one side of the jaw may be engaged, 25 the form of the jaws presenting a double tenon either face of which may engage in the morticed groove in the face of the segment.

I may also provide resilient strips 61 on the forward face of the segment to allow a certain 30 resiliency in the mounting of the jaw and to provide for adjustment of the jaw around the rounded face 53 of the recess. The lower end of the recess 52 is closed at 56 as will be seen in Fig. 8. The upper end of the mortice is closed by a plate 58 held in position by the screw 59.

The forward face of the jaw which engages the pipe may be toothed in various ways and in Fig. 10 I have indicated a desirable form of tooth which may be used. This tooth is provided by transverse grooves 63 in the pipe engaging face 40 of the jaw. Between the grooves are areas 62 which may be knurled to frictionally engage the pipe. The grooves 63 have their upper walls inclined downwardly and inwardly, and are thus adapted to resist downward movement of the pipe 45 relative to the jaw.

In the use of these slips it will be apparent that the slips are each made up of a plurality of 50 flexibly connected jaws or segments which have a limited lateral rocking and vertical adjustment 55 which allows the jaws to adjust themselves to irregularities in the pipe and to irregularities in the slip bowl in which they are seated. In case the slip wedges too tightly between the pipe and the bowl, the upward movement of the pipe will cause the jaw member 25 to be moved upward and jar the segment by the engagement of the shoulders at 23' as previously noted. This will loosen the parts and allow the slip to release. By 60 the use of the wear strips 39 it is possible to adjust the jaws toward and away from the pipe to accommodate different sizes of bowls. Further, by the use of jaws, oblong in cross-section as shown in Fig. 4 adjustment of each jaw may be 65 made upon its segment to accommodate the different sizes of pipe. The slip is, therefore, remarkably flexible and is adjustable in various ways, not only to present different sides or engaging faces to the pipe, but to accommodate pipe of varying diameter.

The device is simple in construction and will have many advantages obvious to those skilled in the art.

What I claim is:

1. A pipe engaging slip comprising a plurality 75

of tapered segments adapted to fit within a slip bowl, pipe engaging jaws carried by said segments, each of said jaws having a plurality of arcuate pipe engaging faces thereon, and reusable means to secure said jaws to said segments whereby either of the pipe engaging faces of each jaw may be turned to contact the pipe.

2. In a pipe engaging slip, a plurality of tapered segments adapted to fit within a slip bowl, flexible connections between said segments, a removable jaw carried by each of said segments, a plurality of concave pipe engaging surfaces on said jaw, and concave-convex bearing surfaces between said jaw and said segment to 15 allow rocking of said jaw on said segment.

3. In a pipe engaging slip, a plurality of tapered segments adapted to fit within a slip bowl, flexible connections between said segments, a removable jaw carried by each of said segments, said jaw having four pipe engaging faces 20 extending longitudinally thereof, said jaw being releasably mounted relative to the adjacent segment so that either of the four faces may be presented for contact with the pipe.

25 4. A slip adapted to be used with either of two different sizes of pipe including a plurality of tapered segments, combination four-faced jaws carried by said segments, said jaws being in opposite pairs, and means releasably securing said 30 jaws to said segments, the opposite faces of said combination jaws forming one pair being formed to engage the same size pipe, said jaws differing in distance across the respective pairs of jaws to compensate for the difference in diameter 35 of the two sizes of pipe to be engaged.

5. In combination with a slip segment, a renewable backing member interposed between said segment and the slip bowl, and a yieldable support between said slip segment and said backing 40 member adapted to be compressed by the wedging of the segment.

45 6. In combination with a slip segment adapted to fit a slip bowl, a renewable backing member interposed between said segment and the slip bowl, said backing member being substantially rectangular in cross-section and adapted to be turned to vary the thickness of the assembled slip segment so as to fit in slip bowls of different sizes.

50 7. In combination with a slip segment, a renewable backing member therefor adapted to engage the slip bowl, means to secure said member in position, and a layer of resilient material between said member and said slip segment.

55 8. In combination with a slip segment, a renewable backing member interposed between said segment and the slip bowl, resilient elements tending to separate said member from said seg-

ment, and means to limit the movement of said backing member.

9. In a device for supporting pipe in wells, a downwardly tapered slip segment, a channel along the front vertical face thereof, a pipe engaging jaw insertable into said channel and securable therein, pipe engaging faces on the front and back of said jaw, said jaw being slidably removable and reversible whereby either of said faces may be positioned to contact a pipe. 10

10. A slip segment, a groove extending vertically therealong, a pipe engaging jaw insertable into said groove, concave pipe engaging areas on the opposite faces of said jaw, and slots in the side of said jaws, the walls of said groove being formed to engage said slots to hold said jaw in place. 15

11. A slip segment, a groove extending vertically therealong, a pipe engaging jaw insertable into said groove, concave pipe engaging areas on 20 the opposite faces of said jaw, slots in the sides of said jaws, the walls of said groove being formed to engage said slots to hold said jaw in place, and a convex bottom in said groove to support said jaw. 25

12. In combination with a slip having a plurality of jaws adapted to engage a pipe, a handle for lifting said slip, a pivoted connection between said handle and said slip whereby said handle normally falls to a lowered position, and 30 means responsive to the raising of said handle to engage the work and thus to force the slip away from the pipe.

13. A slip segment, a longitudinal groove on the forward side thereof, a pipe engaging jaw slideable longitudinally in said groove, concaved pipe-engaging areas on the opposite faces of said jaw, a resilient cushioning means engaging the inner side of said jaw in said groove, the walls of said groove being formed to engage the sides of said 40 jaw to hold said jaw in position. 35

14. A slip segment, a longitudinal groove on the forward side thereof, a pipe engaging jaw slideable longitudinally in said groove, concaved pipe engaging areas on the opposite faces of said jaw, a resilient cushioning means engaging the inner side of said jaw in said groove, a concaved face on said segment engaging said jaw whereby it may have a rocking movement on said segment against the pressure of said resilient means. 50

15. A supporting segment the forward face of which is convex, a pipe engaging jaw having a plurality of concave faces to engage said convex face, means on said segment to retain said jaw movably in position on said segment, rubber 55 cushions at each side of said face to yieldably engage said jaw, and pipe engaging teeth on the concave faces of said jaw.

SAMUEL F. BASHARA.
